UNITED STATES PATENT OFFICE.

CHARLES R. TOST, OF CENTERDALE, RHODE ISLAND, ASSIGNOR TO THE HADLEY COMPANY, OF PROVIDENCE, RHODE ISLAND, A CORPORATION OF RHODE ISLAND.

CORD WATCH BRACELET.

Application filed July 5, 1928. Serial No. 290,290.

This invention relates to watch bracelets of the type in which a cord or other connector, preferably of fibrous material, is looped through suitable openings in the opposite edges of the watch and then, after the cords are cut to the proper length, the free ends of one loop are detachably interconnected with the free ends of the other loop. When using cords of the twisted or braided type the free ends tend to fray; and the principal objects of the present invention are to provide a construction in which the ends of the cords may be conveniently and securely fastened, and substantially enclosed, even when considerably frayed.

For the purpose of illustration, one concrete embodiment of the invention is shown in the accompanying drawings, in which:

Figs. 1, 2 and 3 are front, side and rear elevations respectively; and

Fig. 4 is a section on line 4—4 of Fig. 3.

The particular embodiment of the invention chosen for the purpose of illustration comprises two looped cords 1 having slip rings 2 sliding therealong, a link or holder 3 attached to the free end of the looped cords respectively and a central connecting link 4 which may be of the well-known detachable type in which the cover swings upwardly about the pivot 5 to permit the link to be detached from the next link to the left.

The links or holders 3 each comprises an oblong box having a front 6 and sides 7 and having an open end 8 through which the free ends of the looped cords are inserted, the other end of the box being substantially closed by the pivotal interconnection between the holder and the intermediate link 4. An L-shaped lever 9 is pivoted to the holder by means of integral lugs extending laterally therefrom at the bend therein, these lugs pivoting in openings in the sides 7 as shown in Fig. 4. The end of the shorter leg of the lever is preferably provided with teeth to bite into the cords 1. The lever 9 is preferably of substantially the same width as the interior of the box or holder 3 and it preferably has substantially the same contour as the rear edges of the side 7, whereby the part 9 constitutes a back which substantially closes the rear opening in the holder 6 and lies substantially flush with the rear edges of the side 7 when in closed position.

To insert the loose ends of the cord 1 in the holder 6 the back 9 is swung in a counter-

clockwise direction (Fig. 4) until the long end of the lever or cord gripper is approximately perpendicular to the front 6, whereupon the ends of the cord may be inserted through the open end 8 lengthwise of the cord. By extending the sides 7 in the region of the pivotal interconnection with the back 9, more space is provided for the insertion of the cord when the back is swung to open position. When the cord gripper 9 is then swung back in a clockwise direction to the position shown in Fig. 4 the cord is firmly gripped at a considerable distance from the ends of the cord so that the cord is securely held even though frayed for a considerable distance from the tips. The location of the pivot for the cord gripper near the open end not only enables the gripper to engage the cord at a distance from its tip end but also permits the long leg of the lever to cover the frayed ends, so that the frayed ends are confined and concealed.

I claim:

1. A watch bracelet comprising a series of links pivoted together, the end links comprising oblong boxes substantially closed at the front and sides by the walls thereof and each substantially closed at its inner ends by the pivotal inter-connection with the next adjacent link, the outer ends of said end links being open respectively to receive the free ends of looped cords, a back pivoted to the sides of each end link near the outer end thereof and swinging toward the inner end to lock the ends of the cord near the outer end of the link, said backs closing the major portions of the rear openings in the end links approximately flush with the rear edges of said sides when in closed position, whereby the frayed ends of the cords are substantially enclosed and the cords are gripped at an appreciable distance from the tips of their frayed ends.

2. A watch bracelet comprising a series of links pivoted together and a flexible connector for interconnecting an end link with a watch or the like, said end link comprising an oblong box substantially closed at the front and sides by the walls thereof and substantially closed at one end by the pivotal interconnection with the next adjacent link, and a back pivotally interconnected with the box with means to bite into said connector when the back is swung into closed position, said back closing the major portion of the

rear opening in the box approximately flush with the rear edges of the sides when in closed position.

3. A watch bracelet comprising two connectors, and link means for attaching the end of one connector to the end of the other connector, said means being substantially closed at the front and sides and open at the ends and at the back near the ends, the ends of 10 the connectors extending into said open ends respectively, said means including grippers pivoted to said sides near said ends and swinging toward each other to gripping positions in which they lie substantially flush 15 with the rear edges of said sides wholly between the planes of the sides.

4. A device for interconnecting flexible connectors of watch bracelets and the like comprising link means attaching the end of one connector to the end of the other connector, said means being substantially closed at the front and sides and open at the ends to receive the ends of the respective connectors, said means including grippers pivoted to said sides near said ends and swinging toward each other to gripping positions in which they substantially cover the ends of the connectors. 20 25

Signed at Providence, Rhode Island, this second day of July, 1928.

CHARLES R. TOST.
